UNITED STATES PATENT OFFICE

102,850

DESIGN FOR A TEXTILE FABRIC

George Feinberg, New York, N. Y.

Application September 23, 1936, Serial No. 64,970

Term of patent 3½ years

To all whom it may concern:

Be it known that I, George Feinberg, a citizen of the United States of America, residing in the city, county, and State of New York, have invented a new, original, and ornamental Design for a Textile Fabric, of which the following is a specification, reference being had to the accompanying drawing, forming part thereof, wherein—

The figure is a plan view of a textile fabric showing my new design, with a unit of design marked in dot and dash lines.

I claim:

The ornamental design for a textile fabric substantially as shown and described.

GEORGE FEINBERG.
